UNITED STATES PATENT OFFICE.

CHARLES BENJAMIN SEEM, OF BUFFALO, NEW YORK.

PERMANENT MOLD FOR CASTING RADIATOR SECTIONS AND THE LIKE.

Application filed October 7, 1924. Serial No. 742,141.

To all whom it may concern:

Be it known that I, CHARLES B. SEEM, a citizen of the United States, residing at Buffalo, in the county of Erie and State of New York, have invented certain new and useful Improvements in Permanent Molds for Casting Radiator Sections and the like, of which the following is a specification.

The present invention relates to an improved method of casting radiator sections and the like and the permanent molds for carrying out the same.

The usual method followed of producing radiator section casting is to provide individual molds built up in sand for each casting. This is a very costly and tedious procedure particularly when it is considered that thousands of radiator sections are produced every day by many manufacturers. The introduction of my molds and process for doing the work in radiator plants and other duplicating foundries, whether the castings are made of iron, brass, aluminum or other metals and alloys, would accordingly mean a quite considerable saving in time and labor, and a consequent reduction in wholesale and retail prices of the articles so produced.

My invention now aims at providing a two-piece metal mold, which may be used over and over again, the mold having a collapsible core, such as baked sand suspended in a fixed position in the hollow part of the mold between the cope and the drag.

One embodiment of my invention is illustrated in the accompanying drawing, in which:

Figure 1 represents a top plan view of the mold;

Fig. 2 an end view of Figure 1 with the mold closed;

Fig. 3 a longitudinal section along line 3—3 of Fig. 1 with the core and casting in position;

Fig. 4 a plan view of the mold open exposing the recesses and channels for the casting, and

Fig. 5 a cross section along line 5—5 of Figure 1.

In the drawing, reference numeral 10 represents the cope or top half of the mold and reference number 11 the drag or bottom part thereof. For radiator sections both halves are identical and have been shown such in the drawing, but it is evident that the cope and the drag may have entirely dif-

ferent cavities depending on the section and contour of the casting for which the mold is intended. The mold is to be properly vented.

As indicated in the drawing, it is of rectangular form and the two halves are hinged together along one side as at 12 and provided with clips or locking clamps 13 on the other side, so that the mold can be opened and closed like a suit case. The hollow portion of the mold consists of recesses 14 in each half for the body of the radiator section and channels 15 for the radiating fins thereon. Shallow depressions 16 may also be provided to form bridges or reinforcing strips between the walls of the casting and at each end is furnished a circular pocket 17 for forming the contacting pads 25 between the sections. In order to properly position the core in length direction of the mold these pockets 17 may have a smaller concentric depression as at 18.

Sufficient metal is provided outside the main recess 14 along all edges of the mold so that the surfaces 19 at the central dividing plane of the mold make proper contact to prevent leakage. At 20 is shown the gate or sprue hole one half on each side of the dividing plane. From this gate leads or branches 21 radiate and open into the main recess 14.

The core 22 is collapsible and consists preferably of hard packed sand into which are baked short metal pins or supporting inserts 23 which are of a length corresponding to the height of the cavity of the mold so that the ends of the pins or supporting inserts abut against the top and bottom of the cavity. In this manner the core becomes freely suspended in the cavity so that walls 26 of even thickness are obtained in the casting. As already described the core may be positioned accurately in length direction by engaging with suitable lugs 24 in the depressions 18.

Before commencing the casting the mold is heated to a sufficient degree to prevent chilling. The pouring of the metal is then started and may be done either by pneumatic pressure, vacuum or gravity. As soon as the casting has been completed and the metal has become solid, the locking clamps 13 are removed and the cope 10 swung open or raised thus exposing the casting which may then be lifted out of the drag 11. The core 22 is thereupon removed through the

end openings at 18 of the casting and the interior of the casting cleaned in the usual manner. The pins or supporting inserts 23 will then remain in the casting and form 5 supports for the walls.

Other advantages gained by the use of my permanent molds are: increased production and decrease of imperfect castings with consequent losses. With the pins or supporting 10 inserts remaining in the casting no chipping or dressing off of the same is necessary and work and conditions in general in the foundry are improved.

What I claim as new is:

15. A permanent metal mold for castings com-

prising mating halves, clamps adapted to lock the halves together, a core, means for positioning the core in the mold cavity, said means including lugs on the core and corresponding pockets in the mating mold halves, 20 the mold cavity including longitudinal recesses in the mold halves and transverse depressions connecting the recesses, bracing elements for the casting walls inserted in the core and contacting with their ends the 25 opposite sides of the mold cavity, said elements remaining in the finished casting.

In testimony whereof I affix my signature.

CHARLES BENJAMIN SEEM.
